GUN RECOIL PAD

Louis N. Harbeke, Sacramento, Calif., assignor to
Arrow Recoil Pad Co., Sacramento, Calif., a
corporation of California

Application December 4, 1948, Serial No. 149,976

Term of patent 14 years

(Cl. D30—1)

To all whom it may concern:

Be it known that I, Louis N. Harbeke, a citizen of the United States, residing at Sacramento, in the county of Sacramento and State of California, have invented a new, original, and ornamental Design for Gun Recoil Pad, of which the following is a specification, reference being had to the accompanying drawing, forming a part thereof.

Figure 1 is an elevational view of a gun recoil pad, looking at one side and showing my new design; the opposite side of the pad having the same appearance.

Figure 2 is a cross sectional view of the pad on line 2—2 of Fig. 1.

Figure 3 is a similar view on line 3—3 of Fig. 1.
Fig. 4 is a perspective view of the pad.

I claim:

The ornamental design for a gun recoil pad, as shown and described.

LOUIS N. HARBEKE.
